UNITED STATES PATENT OFFICE.

WILLIAM G. FOSTER, OF DANSVILLE, NEW YORK.

IMPROVEMENT IN THILL-COUPINGS.

Specification forming part of Letters Patent No. 118,600, dated August 29, 1871.

To all whom it may concern:

Be it known that I, WILLIAM G. FOSTER, of Dansville, in the county of Livingston and in the State of New York, have invented certain new and useful Improvements in Thill-Couplings; and do hereby declare that the following is a full, clear, and exact description thereof, reference being had to the accompanying drawing making a part of this specification, in which—

Figure 1 represents the whole device with the thill-iron in place and locked; Fig. 2, a separate view of the device unlocked with the thill-iron removed; Fig. 3, a separate view of the thill-iron; and Fig. 4, a vertical cross-section on the line *x* of Fig. 1.

Like letters of like kinds denote corresponding parts in each figure.

The nature of my invention relates to contrivances for readily locking in place and unlocking thill-irons for carriages; and consists in a rotating hood, which, being revolved in one direction, releases the arm of the thill-iron from an India-rubber-lined slot, in which it works, and, being revolved in the other direction, locks and holds said arm secure in said slot.

In the drawing, A represents a cylindrical piece of suitable metal, provided upon its upper face, near one end, with a semi-cylindrical slot, *a*, having an India-rubber lining, *b*. To the under side of the piece A a suitable metallic strap, B, is secured, one end of which is attached to the axle of the carriage in the usual manner. Upon the slotted end of the piece A the hood C is placed, which hood is provided with a cylindrical opening, *c*, of such size as permits it to slip over and revolve around the end of the piece A. This hood is also provided with a rectangular ear, *d*, of such size that when the hood is in position the

ear extends nearly the whole horizontal length of the slot *a*, leaving only room for the shank of the thill-iron to play by its end, and has sufficient width to cover said slot from side to side. The central under side of this ear is lined with India rubber *e*, contained in a suitable slot. The hood is also provided with a lever or handle, *f*, by which it may be turned, and is secured in place upon the piece A, so that it may revolve thereon by suitable means. The thill-iron D is provided with an arm, *g*, at right angles to its shank *h*, which arm is of a length and size to fit within and turn in the slot *a*.

In the operation of my device, the hood being turned so as to uncover the slot, the thill-iron is inserted therein and the hood turned so that its ear covers the arm of the thill-iron and holds it securely in place. The thill-iron is readily removed by turning the ear back and away from the slot. When the thill-iron is locked in place the lever hangs down and tends by its weight to prevent the hood from turning from the motion of the carriage. The India-rubber packing in the slot and in the ear is for the purpose of preventing rattling.

Having thus described my invention, what I claim as new therein is—

The hereinbefore-described thill-coupling provided with the hood C, substantially as and for the purpose specified.

In testimony that I claim the foregoing I have hereunto set my hand this 1st day of August, 1871.

WILLIAM G. FOSTER.
